UNITED STATES PATENT OFFICE.

ARCHIE M. BANKS, OF TACOMA, WASHINGTON.

SLED-PROPELLER.

SPECIFICATION forming part of Letters Patent No. 670,526, dated March 26, 1901.

Application filed July 10, 1900. Serial No. 23,163. (No model.)

To all whom it may concern:

Be it known that I, ARCHIE M. BANKS, a citizen of the United States, residing at Tacoma, in the county of Pierce and State of Washington, (post-office address Lake View, Washington,) have invented certain new and useful Improvements in Sled-Propellers; and I do hereby declare the following to be a full, clear, and exact description of the invention, such 10 as will enable others skilled in the art to which it appertains to make and use the same.

My invention relates to improvements in skating-machines, and has particular reference to vehicles which are adapted to move 15 upon runners and may be manipulated so that the runners or skates will be actuated to propel the device.

It consists in a machine having a suitable frame, runners or skates for supporting the 20 same, and a propelling mechanism connected with the said runners or skates comprising a crank-shaft, pitmen connecting the cranks of the shaft with the skates, and means carried by the skates for engaging a surface over 25 which the machine is traveling, whereby the reciprocation of the skates will operate to propel the machine forward.

It also consists in certain other novel constructions, combinations, and arrangements 30 of parts, as will be hereinafter more fully described, illustrated, and claimed.

In the accompanying drawings, Figure 1 represents a top plan view of a machine constructed in accordance with the present invention. Fig. 2 represents a side elevation of the same. Fig. 3 is a fragmentary plan view of a portion of the skating-machine, parts of the frame being broken away to better show one of the skates. Fig. 4 represents 40 a top plan view of a machine adapted to be propelled by foot-power. Fig. 5 represents a side elevation of the same. Fig. 6 is a detail cross-section through one of the runners or skates.

45 A machine built in accordance with this invention may be constructed so as to be propelled by mechanical power or by foot-power applied by an individual riding upon the same.

50 In Figs. 1 and 2 of the drawings I have shown the machine as adapted to be operated by any suitable motive power, while in Figs.

4 and 5 of the drawings the device is provided with a propelling mechanism similar to that commonly used upon bicycles.

In carrying out the features of the invention the skating-machine comprises, preferably, a frame, as 1, of any suitable structure, and a series of supporting skates or runners 22. The frame 1 may be considerably lightened by cutting out large portions of the same, as illustrated in the drawings. The skates or runners 22 are provided with upwardly-extending standards 33, which project through longitudinally-arranged slots or 65 openings 44 in the frame 1. These standards 33 are connected with the motive power in such a manner that the skates may be moved back and forth in the slots 44 for propelling the machine. About centrally of the frame 1 and 70 transversely thereof I mount a power-shaft 5, which is supported in suitable bearings 66, carried by the said frame. The shaft 5 is provided with suitable cranks, as 77, which are connected with the standards 33 of the skates or runners by pitmen 88. The pitmen 88 are pivotally connected with the standards by means of bolts, as 99, and spacing-sleeves, as 1010 and 1111, are interposed between the ends of the pitmen and the said standards 33. The 80 length of the spacing-sleeves 1010 and 1111 is regulated to accommodate the pitmen to the positions of the cranks 77 on the crank-shaft. Thus the sleeves 1111 at the rear of the machine are longer than the sleeves 1010 85 at the forward end of the machine, since the bolts passing through the said sleeves 1111 are connected with pitmen which extend to the innermost cranks 77. By this arrangement the pitmen will not conflict with each other when the crank is actuated. The crank-shaft 5 may be provided with a centrally-arranged power-receiving crank, as 12, which may be connected with any suitable source of power (not shown) for rotating the crank-shaft 5. The rotation of said crank-shaft will, 90 by means of the cranks 77 and the pitmen 88, cause the skates or runners to reciprocate in the slots 44. In order that the skates or runners may be able to engage or take a hold of the surface over which they are traveling, they are provided with pivoted dogs, as 1313, which are pointed at their free ends, so that they will stick into the ice or snow or

other surface over which the machine is being propelled. A simple manner of securing the dogs to the runners is illustrated in the drawings, from which it will be seen that the 5 said dogs are bifurcated, as at 14 14, so as to receive the rear edge of the runners, a pivot-pin, as 15 15, securing each of the dogs to its respective runner. The dogs 13 13 are held in engagement with the surface of the ice or 10 other substance over which the machine is traveling by means of springs, as 16 and 17, which are interposed between the said dogs and the pitmen 8 8. In order to attach the 15 springs to the said pitmen, they are provided with laterally-projecting arms, which are made of sufficient length to extend over the slots 4 4. The springs 16 and 17 may thus extend downwardly through the said slots to the dogs 13 and will not be interfered with by any 20 of the working parts. These springs serve to hold the dogs in engagement with the traction-surface, so that a positive hold will be obtained upon the same at each forward movement of the skate. I contemplate using either 25 a coiled spring, as at 16, or a flat steel spring, as at 18, and at either end of the machine, as may be found most desirable.

In order to support the frame 1 upon the skates in such a manner that there will be 30 little or no friction between the parts, I interpose between the said runners and the frame antifriction-rollers, as 19 19. These rollers 19, as seen in Fig. 3 of the drawings, are arranged upon each side of the skate, so 35 as to engage the frame 1 upon each side of the slots 4 4. These antifriction-rollers make it possible for the skates to be moved back and forth readily beneath the frame which they support. At a suitable point I provide 40 a guiding skate or runner 20. This is preferably located at the forward end of the frame 1 and has a guiding standard or stem, as 21, which projects upwardly through a suitable bearing in the frame 1 and may be provided 45 at its upper end with a guiding handle or lever, as at 22. It will be apparent that tiller-ropes might be secured to such a handle or lever, if desired, and run to any point upon the frame of the machine, so that the person 50 guiding the machine need not necessarily be at the front of the same.

In manufacturing machines of this kind they may be made quite light, if desired, and may be so arranged as to be propelled by foot- 55 power. As seen in Figs. 4 and 5 of the drawings, for instance, the machine may be provided with a propelling mechanism similar to that used upon bicycles. In arranging for this manner of propulsion a sprocket-wheel, 60 as 23, can be secured to the driving-shaft and may be connected by means of a sprocket-chain 24 with an actuating sprocket-wheel 25. The sprocket-wheel 25 is supported upon a suitable shaft 26, finding bearings, as at 65 27 27, in standards upon the frame 1. The shaft 26 carries at each end a crank-arm, as 28 28, which are furnished with pedals, as

29 29, of any desired type. A seat 30, adjustably supported upon the frame 1, is preferably arranged at a proper position above 70 the pedals 29 29. This seat may be of the type ordinarily used upon bicycles, and its supporting-post 31 may be adjustably mounted in a standard 32, as illustrated in Fig. 5 of the drawings. This driving-gear is preferably arranged sufficiently near to the guide-post 21 so that the occupant of the saddle 30 will be within easy reach of the handle-bar 22. By this simple arrangement the ice-machine may be propelled by a person and also 80 guided by him, if desired.

The skates or runners may be made in any suitable manner, and I prefer to form them, as shown in Fig. 6 of the drawings, of two outer plates 33 33 and an intermediate spacing-block 34, the parts being firmly bolted or otherwise secured together. The spacing-block 34 is made narrower than the plates 33, so that the said plates project below the spacing-block, forming a groove between them, 90 and the edges of the plates are thus left so prominent as to form the wearing-surfaces of the skates or runners. The runners constructed in this manner, with grooves or gutters in them, take hold of the traction-surface, so that the machine is not easily swerved from its proper course.

From the foregoing description the operation of the machine will be readily understood. The revolution of the crank-shaft 5 100 causes first one set and then the other set of the runners to be forced forward. When going forward beneath the frame 1, the dogs 13 slide over the traction-surface until the skates stop their forward movement and begin a rearward motion. The sharp engaging points of the dogs then hold the skates from retreating upon the traction-surface and the machine is propelled forward with respect to the same. By the arrangement of the cranks 105 one pair of the skates is always holding the machine against rearward movement, while the other pair of skates is moving forward to obtain a new hold for further propulsion.

The machine is exceedingly simple in its 115 construction and arrangement and not likely to get out of order. It can be supplied with various kinds of power for operating the propelling mechanism without departing from the spirit of the invention.

Having thus described the invention, what is claimed as new, and desired to be secured by Letters Patent, is—

1. A skating-machine, comprising a suitable frame, reciprocating runners arranged 125 in tandem, one behind the other, and so as to support the frame, traction engaging means carried by the said runners, and means upon the frame for reciprocating the runners toward and away from each other, whereby a forward 130 motion of the machine may be secured.

2. A skating-machine, comprising a frame, runners arranged one behind the other on each side of the machine, and supporting the

frame, a power-shaft carried by the machine and connected with the said runners, and surface-engaging dogs carried by the runners, the structure being such that the runners may 5 be reciprocated with respect to the frame of the machine so as to move to and from each other for propelling the same.

3. A skating-machine, comprising a frame, runners supporting the same and extending 10 upwardly through guiding-slots formed in the machine for directing the runners in a back-and-forth movement, a crank-shaft mounted upon the frame, pitmen connecting the cranks of the said shaft with the runners, surface- 15 engaging dogs carried by the runners, and means interposed between the said pitmen and said dogs for holding them in engagement with the surface traveled, the construction being such that upon rotating the crank-shaft 20 the runners will be moved back and forth for propelling the machine.

4. A skating-machine, comprising a frame, supporting runners mounted beneath the same, antifriction means carried upon the upper edges of the runners and supporting the frame, a crank-shaft provided with cranks upon the said frame, pitmen connecting the cranks with standards on the runners, surface-engaging dogs carried by the said runners, and springs interposed between the pitmen and the dogs for holding the latter in engaging contact with the traction-surface, substantially as described.

5. A skating-machine, comprising a frame 35 having longitudinal guiding-slots formed therein, runners underneath and engaging bearing-surfaces on the frame for supporting it, standards upon the said runners projecting upwardly through the guiding-slots of the frame, a crank-shaft mounted upon the frame, cranks formed therein, pitmen secured to the said cranks and pivotally connected with the standards of the runners, surface-engaging means carried by the said runners, and means 40 for guiding the machine, the structure being such that upon rotating the crank-shaft some 45 of the runners will be moved forward to ob-

tain a new hold upon the traction-surface, while the others engage the said surface, so that the machine is pushed forward with respect to the same, substantially as described. 50

6. A skating-machine, comprising a frame, reciprocating runners arranged one behind the other on each side of the machine for supporting it, a power-shaft for reciprocating the 55 said runner, having double cranks on each side of the machine, pitmen connecting all the runners with the cranks, means carried by the runners for engaging the traction-surface, so that they will not slip rearwardly 60 over the same, means for actuating the crank-shaft, comprising a sprocket-wheel mounted thereon, a sprocket-chain connecting the said wheel with an actuating sprocket-wheel, an actuating sprocket-wheel, a shaft carrying the 65 same, pedals secured to the said shaft, and a seat for supporting the operator above the pedals, the structure being such that by actuating the pedals the crank-shaft may be caused to reciprocate the runners toward and 70 away from each other on each side of the frame, and thereby propel the machine.

7. A skating-machine, comprising a frame, reciprocating runners arranged one behind the other on each side of the machine and supporting the frame, surface-engaging means secured to each of the runners, means for reciprocating the runners, comprising a shaft having double oppositely-arranged cranks on each side of the frame, pitmen connecting the 75 runners with the cranks so that some of the runners are moved in one direction while the others engage the surface traveled and are pushed against in the opposite direction, a guiding-runner mounted beneath the frame, a 80 guiding stem or standard therefor, and a handle-bar for turning the same, substantially as described.

In testimony whereof I hereunto affix my signature in presence of two witnesses.

ARCHIE M. BANKS.
